US0D1084922S

(12) **United States Design Patent** (10) Patent No.: **US D1,084,922 S**
(45) Date of Patent: ** Jul. 22, 2025

(54) **ELECTRIC BICYCLE**

- (71) Applicant: **INVANTI (BEIJING) TECHNOLOGY CO., LTD.**, Beijing (CN)
- (72) Inventors: **Chunyuan Xu**, Beijing (CN); **Lijian Li**, Beijing (CN); **Chongyang Shi**, Beijing (CN); **Jianguo Jiang**, Beijing (CN)
- (73) Assignee: **INVANTI (BEIJING) TECHNOLOGY CO., LTD.**, Beijing (CN)

(**) Term: **15 Years**

(21) Appl. No.: **29/923,794**

(22) Filed: **Jan. 2, 2024**

(30) **Foreign Application Priority Data**

Dec. 19, 2023 (CN) 202330835365.6

(51) **LOC (15) Cl.** **12-11**

(52) **U.S. Cl.**

USPC **D12/111**
